UNITED STATES PATENT OFFICE.

JAMES C. POTTER, OF PAWTUCKET, RHODE ISLAND.

RING SPINNING OR TWISTING MACHINE.

1,401,729.

Specification of Letters Patent. Patented Dec. 27, 1921.

Application filed September 1, 1921. Serial No. 497,616.

To all whom it may concern:

Be it known that I, JAMES C. POTTER, residing at Pawtucket, county of Providence, State of Rhode Island, a citizen of the United States, have invented certain new and useful Improvements in Ring Spinning or Twisting Machines, of which the following is a specification.

With the spinning mule, the much desired soft finish yarn is produced, but it is at the expense of quantity production. For example, the carriage may take eight seconds on the running out or stretch in which the twist is being done; three seconds may be taken while the carriage is on the latch; and the run in during which the winding is done takes about three seconds. Thus out of about fourteen seconds, winding on the bobbin occurs during three of them. In ring-spinning, inasmuch as twist and wind take place simultaneously, a much greater quantity production than with the mule is possible, but with the ring-spinning machines with which I am familiar, and which are practicable, in which the rings move with reference to the bobbins in laying on the thread, the twist must be so tight or close that the spun thread is hard and lacking in the soft finish which is attained by the mule.

An object of my invention is to secure in ring-spinning the soft finish yarn of mule spinning and the rapidity of production which is possible in ring spinning.

Another important object of my invention is to eliminate, or reduce to an unobjectionable degree, the torsional strains on the draw or feed rollers by which the roving is fed to the bobbins. These rollers sometimes are forty feet long and so small in diameter as an inch for the front and seven-eighths for the middle and back rollers. Obviously, rollers so long and so slender, and so weighted as they are to make them grip the cotton, must, when the power to rotate them is applied at one end, as is ordinarily the practice, undergo great torsional deformation when their revolution is started. The consequences of this great twisting strain are seen in both the machine and its work. First, the rollers themselves may break or be otherwise injured from the twist, such injury taking place at their journals which are of less diameter than the rollers, and

where the roller sections are united or joined. Second, irregularity in the feed of cotton may result due first to slow movement of the retarded remote portions of the rollers which results in thin yarn due to insufficient feed from the rollers, and second, to sudden speeding up of the retarded remote portions of the rollers under the reaction of such retarded portions, so that a greater quantity of cotton will temporarily be delivered to certain of the spindles than should be, with the consequence that there will be a thickened length of twist that might show and be objectionable in the woven goods.

Still another important object is to assure the proper lubrication of the spindle bearings. By the customary oiling devices, each spindle must be separately oiled by the application of oil thereto by a boy or attendant. Often by carelessness or inadvertence he may fail to oil some of them with the result that the spindle revolution will be slowed down and wear of and hurt to the spindle take place thus injuriously affecting the twist and making bad yarn, and causing breakdown of the yarn.

The achievement of the objects named, (which is done by my invention), concerns, therefore, quantity and quality of the product, wearing qualities and life of the machine, and cost of maintenance and operation. These benefits and other flowing from my invention will be set forth hereinafter in this specification and other will be perceived by those skilled in the art without being set forth.

In the drawings:

Figure 1 is a side elevation with portions broken away of a ring-spinning machine embodying my invention, omitting a portion of the builder motion gearing for greater clearness;

Fig. 2 is an end elevation thereof;

Fig. 3 is a top plan view of the middle portion thereof;

Fig. 4 is a vertical section on line 4-4 of Fig. 1;

Fig. 5 is a horizontal section on line 5-5 of Fig. 4;

Fig. 5^a is a like view of a different separator;

Fig. 6 is a detail horizontal section on line 6-6 of Fig. 1;

Fig. 7 is a top plan view of one of the

carriages with spindles and tin roller assembled thereon ready for setting upon its slides;

Fig. 8 is a side elevation of the same showing the carriage in position on the slides;

Fig. 9 is a view in the nature of a perspective diagram showing the builder motion gearing;

10 Fig. 10 is a detail view in section of the spindle oiling device.

Before describing in detail the machine shown in the drawings as one very good embodiment of my invention, I will give a general description thereof. Instead of moving the ring rail to carry the rings up and down with reference to the spindles, I stationarily support the ring rails, and transverse the spindles, mounting the latter, and 15 the tin roller which drives them, on a vertically movable carriage to which motion is imparted by a builder motion which in general respects is of a commonly used construction although in some particulars, as 20 will hereinafter appear, it possesses novel features of importance and value. By keeping the rings stationary and transversing the spindles, it will be seen that the angle at which the thread runs from the 25 thread guide to the traveler does not change, nor does the length of thread from the guide to the traveler change, as is the case when the rings move. When the rings move and they are at the upper part of the bobbins 30 the thread extends at such an angle from the guide that the thread makes such a sharp turn over the traveler, on its way to the bobbin, that a weak place in the thread at the turn is readily broken; and again the 35 length of thread from guide to traveler is so short that if a thin or weak place occurs, the pull on the thread by the traveler is apt to break it. To meet these conditions, when 40 a traveling ring is used, the twist must be made tight in order to give sufficient 45 strength to the thread to resist breakage, with the result that the yarn produced is hard and lacking in the qualities which 50 make the soft finish desirable. By using 55 the stationary rings, therefore, the thread between the guide and the traveler has a length and angle that are constant, the length being substantially the maximum, and the angle being substantially the same as the 60 length and angle that are possible when the rings travel over the bobbins and they are at the bottom or lowest point of their travel. I thus remove the conditions that favor breakage of the thread, and, hence, 65 do not need to make the twist objectionably tight to safeguard against such conditions, and employ a traveler of a weight that will result in a twist giving a soft finish. The 70 elimination or reduction of the likelihood 75 of breakage of the threads is of great im-

portance in increasing the output of the machine because it saves the loss of time and trouble required to tie the broken thread, and the likelihood of an insufficiently filled bobbin.

One of the important advantages that I derive from having the ring-rail stationary is the ability to use the tube-form separator, which, obviously, is the best form in that it controls ballooning throughout the revolution of the spindle without hurtful effect on the yarn. With plate-form separators, which is the form that must be used when the ring-rail traverses over the spindles, the yarn, in ballooning, whips against and then off them, wearing the yarn away and producing fly which accumulates and pulls through in bunches with the yarn. With the traversing rail, the tube-form separator cannot be used because in the upper part of 80 the ascending movement of the ring-rail, there is not room enough below the thread guides to accommodate such tubes.

Another important advantage from the stationary ring-rail is that, being stationary, 90 it can be so firmly or rigidly mounted that trembling or chattering with danger of breaking the yarn between the feed rollers and the bobbins cannot occur.

Instead of driving the feed rollers from 95 a head at the end thereof, I drive them from a head at midlength, and thus by shortening the rollers eliminate or reduce to a negligible quantity the torsional deformation of such rollers. It is possible for 100 example, with the same number of spindles to reduce the length of the rollers on either side of the point of application of the power thereto, to rotate them, to substantially half the length of the rollers having the rotating 105 power applied at one end; or the length on each side the point of application of power could be greater than half the length of rollers driven at the ends, up to an unobjectionable length, having regard to torsional deformation, and thus the spindle 110 capacity of the machine be increased. The spindles and their tin rollers on either side of the central power applying or rotating head are carried by independent carriages 115 and they are so connected that they counterbalance one another, so that the weight of one and the parts carried thereby, when descending, helps raise the other and the parts it carries.

Instead of providing for the separate and individual oiling of each spindle in a row, I connect all the oil passages in the bolster case in the same row with a single pipe or tube which at one end has a cup 120 or reservoir into which oil is poured and which is kept at the desired level to assure gravity feed of oil to the spindles and to the proper level in the bolster case. Thus, with this method of oiling applied to my 125 130

ring-spinning or twisting machine, a single carriage supports two rows of spindles, the oil tubes for the two rows, and the tin roller for such two rows of spindles, and as this carriage rests freely upon the slides by which it is traversed, without being bolted or otherwise attached thereto, it, with the parts carried thereby, constitutes a unit.

Taking up now the description in detail of the machine shown in the drawings, the main frame includes two foot pieces, 10, at opposite ends, and two spaced apart heads, 11, at midlength, by which heads are supported the driving mechanism. One of the heads and one of the foot pieces of each pair are connected by two parallel angle bars, 13, and below the latter are a pair of parallel ring-rails, 14, each supported immovably by being bolted to a samson, 15, at midlength, and also, preferably by bolting at the ends to the head and foot piece between which the rails extend. The ring rail has at its rear edge an integral upstanding flange, 16, that reaches to the bottom edge of the front vertical flange of the near angle bar, 13. The ring-rails have rings, 17, of usual form, each with a traveler, 18, and each concentric with a hole, 19, for the vertical passage or travel of one of the spindles, 20, and the bobbin, 21, thereon, the spindles being secured in a row or line of the desired number to a vertically movable spindle rail, 22. There are two parallel rows of spindles and, therefore, two rails, 22, and the latter, in the case of each unit lying between a head, 11, and a foot, 10, are connected at the ends by a pair of cross bars, 23, and by one or more intermediate cross bars, 23, and at the center of each cross bar, 23, midway between the two rows of spindles, are bearings for the journals of a tin roller, 24, which by bands, 25, is belted to the spindles appropriate to such roller. Thus the two rows of spindles and the tin roller for each unit are mounted on a carriage composed of a pair of spindle rails and a pair of cross bars, 23, that connect them at the ends, and at intermediate points. The said carriage is supported by the spindle rails resting upon vertical bolts, 26, that, respectively, pass through lugs, 27, that project horizontally from vertical slides, 28, that, respectively, are mounted upon vertical guides that are bolted or otherwise attached to head, foot, and samson. Each slide, 28, has rack teeth, 29, with which a pinion, 30, on a horizontal shaft, 31, meshes, (said shaft being rotated by the builder motion hereinafter described), so that by the revolution of said shaft, the frame which carries the two rows of spindles and the associated tin roller may be raised and lowered, and thereby the vertical travel of the spindles and their bobbins with reference to the rings, may be

produced. The frame rails, 22, since they rest upon the bolts, 26, without being attached to the slides, 28, should there be any want of parallelism of the slides, 28, due to improper setting of head and foot pieces 70 and samsons, or warping of the latter, no trouble will arise therefrom because the loose or floating support of the spindle rail frame on said slides will allow whatever horizontal play is necessary to compensate 75 for such imperfection in setting or of material. Bolts, 26, are employed because they enable the level of the spindle-rail frame to be independently adjusted, should the supporting frame not be properly leveled. 80 All or certain of the bolts, 26, say one on each side, have conical ends that enter corresponding sockets in the underside of the spindle rails and thereby the carriage is positioned easily. 85

A most important advantage from my manner of mounting the spindle and tin roller supporting carriage, loosely resting it on its supports, such as the bolts, 26, is that such carriage may be assembled as a 90 unit, complete with the spindles, tin roller and bands between roller and spindles and then lifted and put into place upon said supports within the already erected supporting framework composed of the connected head and foot pieces, leaving only the ring-rails and the samson to be put into place after the said carriage has been placed. Thus erection and assemblage of the machine is easy and convenient. 100

On the shaft of each tin roller in the space between the two heads, 11, is a pulley, 32, from which a belt, 33, passes upward to an idler pulley, 34, journaled in bearings in a bracket, 35, mounted on the top of 105 the two heads, and to a counter shaft pulley, 36, from which power is taken to drive the tin rollers, the feed rollers and the builder motion, the shafts of the idler and the countershaft pulleys being at right angles to the 110 tin rollers axes. Inasmuch as the spindles and tin roller forming one unit rise when those of the other unit descend, it will be seen that the slack in the belt, 33, caused by the ascent of one, is exactly taken up by 115 the descent of the other, and, hence, the belt always remains taut. A screw device, 37, is provided to adjust the idler pulley to give the proper tension to the belt, 33.

The builder motion comprises a lever, 38, 120 of substantial length that is located substantially midway between the two lines of spindles, and being pivoted near the floor by a pivot, 39, extends upward and near its upper end has a radially movable slide 125 block, 40, to opposite sides of which are attached two chains, 41, that extend in opposite directions and respectively pass over idlers, 42, located on opposite sides of the lever and each passing to a sprocket wheel, 130

43, on one of the shafts, 31, so that when the lever, 38, swings in one direction, the two shafts, 31, of one unit, (which are geared together by two idlers, 44, meshing with gears, 310, to rotate in the same direction), will be revolved to move the spindle carriage of that unit downward, and the two shafts, 31, of the other unit will be revolved to move the spindle carriage of the other unit upward, and vice versa. (See Figs. 3 and 9.) The swing to and fro of the lever, 38, is controlled by a heart cam, 45, the periphery of which contacts with a roller, 46, on the lever, 38, the lever having a weighted arm, 47, to hold it against the cam. The gearing to drive the cam is described hereinafter.

By having the two units so tied together by the gearing of the builder motion that one moves up when the other descends, the weight of one counterbalances that of the other, and by having the spindle rails of the same unit connected, or carried by the same frame, so that both move in the same direction, or up and down together, an unbalanced condition is avoided such as would exist if they moved in opposite directions at the same time.

The slide block, 40, as usual, is automatically shifted along the lever, 38, or builder arm, to change the length of throw thereof to taper off the ends of the cop, by a pawl and ratchet device, 48, of usual construction, which is adjustable to suit the winding of yarns of various counts, and as the lever stands vertically upright, its upper end, where the ratchet feed is located, is comfortably accessible to an operative for any hand manipulation of said ratchet device that may be necessary. The ratchet wheel has a handle, 49, for hand manipulation.

In order to have the body portion of the cop truly cylindrical, it is essential that variation of the speed of travel of the spindles through the rings be avoided, and this can only be accomplished by having the point of connection of the lever, 38, with the chain, 41, move in as near a straight line as possible. I achieve this by my arrangement of the lever, which gives it such length that the arc described by said point departs very little from a straight line.

It is desirable, in the interest of getting as many spindles as possible in a given space, to set them as close together as possible. In locating them attention must be given to the "ballooning" of thread in passing from the thread guides to the travelers. With the rings stationary and the spindles traversing in building up, the effect of ballooning is greatly diminished, and, hence, the spindles can be placed closer together than is possible where ballooning is greater. This is due to the fact that the length of thread from the guide to the traveler is less than the maxi-

mum length of the thread from guide to traveler when the ring-rail traverses the cop, and I can make it shorter because the minimum approach of the bobbin nose to the guide is shorter than the minimum distance that is practicable between the guide and the ring, without too sharp an angle of the thread when the ring is the traversing member. However, I prefer to provide separator devices between adjacent spindles to control ballooning, which are in the form of a tube, 50, for each spindle that is concentric therewith, and thus surrounds the bobbin on the spindle, and presenting a continuous surface to the thread, gently, but efficiently, and without the friction and wear that results from whipping against a flat plate separator, such as is ordinarily used. The interior surface of the tube is highly polished and its edges rounded so that the thread passes over it without friction. To enable the thread to be passed into the tube and yet prevented from accidentally escaping therefrom, an obliquely extending slit, 51, may be provided, or as shown in Fig. 5, the slit, 510, may be parallel with the axes of the spindle but having the edges lap past one another, the inner edge lapping in the direction in which the thread travels around in the tube and therefore in the direction opposite that in which it must move to pass out through the slit. The separator tubes are supported from the vertical flange of the ring-rail and preferably by means of an arm, 52, by which they are pivoted to a bracket, 53, bolted to said flange. The separator tubes are supported a substantial distance above the rings to allow access to the travelers in piecing broken ends, the yarn being threaded in the traveler, and also to give them a location which will encompass the ballooning thread where its throw is greatest. These separator tubes are also useful as shields or guards which protect the threads from drafts of air occurring about the machine which blow the threads about. This pivotal connection is provided for convenience in doffing, for when the spindle is in its lowest position, the separator tube can be swung upward and against the ring-rail flange, out of the way, as shown by dotted lines in Fig. 4.

The creel, 54, and the feed rolls, 55, are of usual or any desired construction and need not be described in detail. Power to drive the feed rolls is taken by gearing from the tin roller of each unit. Thus a pinion, 56, on the tin roller shaft meshes with a gear, 57, on a shaft having a sprocket wheel, 58, which is connected by a sprocket chain, 59, with a sprocket wheel, 60, and on a shaft with the latter is a gear, 61, which meshes with an intermediate, 62, that meshes with a gear, 63, on one of the front rollers. Between the gear, 63, and a similar

gear, 64, on the other front rollers are two intermediates, 65, and thus motion is transmitted to such other feed roller. Power to drive the builder motion is taken from one of the intermediates, 65. A sprocket wheel, 66, on the shaft of such intermediate, is connected by a sprocket chain, 67, with a sprocket wheel, 68, which by bevel gears, 69, one of which is on a shaft, 70, rotates the latter which has a worm, 71, that meshes with a worm wheel, 72, on the shaft, 73, to which is fixed the builder arm vibrating cam. The gear connections with the feed rollers include proper change gears to enable the speed to be changed for different counts and twists.

The tube, 74, having the oil cup, 75, at one end for conveying oil to all the spindles in a row, is clamped to the arm, 76, of the bolster case by a horizontal block, 77, the tube fitting in a half round groove in the top of the bolster case arm and one in the underside of said block. A single screw, 78, clamps the block against the top of the arm, 25 and against the tube. A vertical oil passage, 79, leads from the bottom of the tube to deliver oil to the bearings within the bolster case, the bottom of the tube being provided with an outlet, 80, to the top of said passage. 30 Said outlet is advantageously made by a punch introduced through a hole, 81, in the top of the tube, the oil outlet, 80, at the bottom being thereby formed with a lip, 82, that enters the top of the passage, 79, and 35 such lip being spaced from the side walls of the passage, the escape or leakage of oil into the joint between the tube and the bolster arm and clamping block is prevented. Leakage of oil is further prevented by 40 reason of the very close fit between the tube and the bolster case arm and clamp block. The hole, 81, in the top of the tube permits hand-oiling if desired, and affords access to the tube outlet, 80, for cleaning when 45 necessary. Said hole, 81 is covered by a cover plate, 83, that fits within a milled grooved, 84, in the top of the clamp-block, and is pivoted thereto to swing up and down, and said cover has, as usual, a tail, 50 85, that overhangs the spindle whirl to form a doffing latch.

My invention is applicable to twisting as well as spinning, and it is to be understood that while a machine constructed in close conformity with what is illustrated in the drawings is a satisfactory embodiment of my invention, I do not restrict myself to such a construction, and I embrace as within my invention whatever construction is defined by or is included within the terms or scope of the following claims.

What I claim is:

1. In a ring-spinning or twisting machine, the combination of rings and travelers 65 thereon, a stationary support for such rings,

thread-feeding means situated a fixed distance from the rings, spindles, spindle rotating means, a carriage that supports the spindles, and a builder motion for traversing said carriage and causing movement of 70 spindles and bobbins supported thereby to and fro through the rings, the travelers deriving their motion only from the pull of the threads as the latter are wound upon the bobbins.

2. In a ring-spinning or twisting machine, the combination of rings and travelers supported thereon, a stationary support for such rings, thread-feeding means situated a fixed distance from the rings, a carriage 80 that supports spindles and spindle rotating means, and a builder motion for traversing said carriage and causing the movement of spindles and bobbins supported thereby to and fro through the rings, the travelers deriving their motion only from the pull of the threads as the latter are wound upon the bobbins.

3. In a ring-spinning or twisting machine the combination of rings and travelers thereon, a stationary support for such rings, thread-feeding means situated a fixed distance from the rings, a carriage, spindles mounted on and moving with the carriage, a tin roller 90 mounted on and moving with the carriage, hands from the tin roller to the spindles to rotate the spindles, and a builder motion for traversing said carriage, and causing the movement of spindles and bobbins supported thereby to and fro through the rings, 95 the travelers deriving their motion only from the pull of the threads as the latter are wound upon the bobbin.

4. A ring spinning or twisting machine having a pair of movable spinning element 105 supporting carriages spaced apart at substantially midlength of the machine, a single builder motion arm located within the space between the carriages, and an operative connection between the latter and said carriages. 110

5. A ring-spinning or twisting machine having a builder motion that comprises a vertically extending lever pivoted at one end, two spindle-supporting carriages spaced apart substantially at midlength of the machine and said lever being situated in such space, and an operative connection between said lever and both carriages.

6. A ring-spinning or twisting machine having a pair of vertically movable spinning 120 element supporting carriages, a builder motion having oppositely acting driving connections with said carriages, said carriages counterbalancing one another through such connections said carriages being spaced apart 125 at substantially mid-length of the machine and said builder motion comprising a vibratory lever situated in the space between the carriages.

7. A ring-spinning or twisting machine 130

- having a pair of movable spinning element supporting carriages, a single builder motion arm, and an operative connection between the latter and each of said carriages 5 said carriages being spaced apart at substantially mid-length, and said builder motion arm being located in the space between the carriages.
8. A ring-spinning or twisting machine having a pair of movable spinning element supporting carriages, a single builder motion arm, and an operative connection between the latter and each of said carriages, one of said connections producing carriage motion 15 in a direction opposite that of the other said carriages being spaced apart at substantially mid-length, and said builder motion arm being located in the space between the carriages.
- 20 9. A ring-spinning or twisting machine having a pair of oppositely movable carriages, rotatable spinning elements mounted on each carriage, means simultaneously moving such carriages in opposite directions, a rotatable member mounted on and moving with each carriage having a driving connection with said spinning elements supported by the carriage to rotate such elements, a rotatable power delivering member, and means for transmitting power therefrom to both said rotatable members on the carriages that maintain a constant power transmitting connection therewith at all points in the movement of said carriages.
- 25 10. A ring-spinning or twisting machine having a pair of oppositely movable carriages, rotatable spinning elements mounted on such carriages and moving therewith, means for simultaneously moving said carriages in opposite directions, and means for rotating the spinning elements on both carriages comprising stationarily mounted drive 30 and idler pulleys, a pulley mounted on each carriage and moving therewith, and a belt running from the drive pulley to the idler pulley and about each carriage pulley.
11. A ring spinning or twisting machine having a pair of vertically movable spinning element supporting carriages spaced apart substantially at mid-length of the machine, 35 means for moving said carriages simultaneously in opposite directions, means for rotating the spinning elements of each carriage comprising a pulley mounted on and moving with the carriage, stationarily mounted driving and idler pulleys, and a belt running from the driving pulley to the idler pulley, and over each of the carriage supported pulleys, such carriage-supported pulleys being situated in the space between 40 the carriages.
12. A ring-spinning or twisting machine having a builder motion that comprises a vertically extending lever pivoted at its lower end, transmitting motion from a point 45 at or substantially at its upper end, and two oppositely movable spindle-supporting carriages independently connected with said lever said carriages being spaced apart substantially at midlength of the machine and 50 said lever being situated in such space.
13. A ring-spinning or twisting machine having two groups of spindles, feed rollers for the respective groups of spindles, the groups of spindles and the feed rollers being spaced apart substantially at mid-length 55 of the machine, and a single power head for both groups of spindles and the feed rollers situated in such space, said power head including separate operative connections with 60 the respective feed rollers.

In testimony whereof I hereunto affix my signature.

JAMES C. POTTER.
